UNITED STATES PATENT OFFICE.

BEULAH L. HENRY, OF CHARLOTTE, NORTH CAROLINA, ASSIGNOR OF ONE-HALF TO
WILLIAM THOMAS WOODLEY, OF CHARLOTTE, NORTH CAROLINA.

PARASOL.

1,079,240.

Specification of Letters Patent.

Patented Nov. 18, 1913.

Application filed September 28, 1911. Serial No. 651,722.

To all whom it may concern:

Be it known that I, BEULAH L. HENRY, a citizen of the United States, residing at Charlotte, in the county of Mecklenburg and State of North Carolina, have invented new and useful Improvements in Parasols, of which the following is a specification.

The general objects of the invention are to adapt a sun shade or parasol to be folded into a comparatively small compass when not in use and to combine a vanity case with the handle thereof.

Other objects will appear and be better understood in the following description taken in connection with the accompanying drawings, in which—

Figure 1 is a side elevation of the device partly in section. Fig. 2 is a detail section showing the means for clamping the central portion of the cover to the stick.

Fig. 3 is a detail section showing the means for attaching the cover to the frame. Fig. 4 is a detail perspective partly in section of the runner and a fragment of the stick.

Fig. 5 is a side elevation of the device telescoped or folded. Fig. 6 is a detail partly in section and elevation of the parts folded and with the cover removed. Fig. 7 is a detail partly in section and elevation of the tip and the section in which the said tip telescopes.

Fig. 8 is a detail perspective of the attachment for the handle. Fig. 9 is a broken vertical section, partly in elevation illustrating the supporting means for the runner. Fig. 10 is a transverse section of the same taken just above the supporting means.

a indicates the stick which consists of the sections 5 adapted to telescope one into the other. Spring catches 6 have end portions 7 adapted to enter recesses 8 in the sections when the same are extended in order to hold the said sections against collapsing.

b designates the frame, the ribs 9 of which pivotally connect, in the usual manner to the notch 10 suitably secured to the section

into which the ferrule or tip 11 telescopes. 12 indicates the cover formed of any suitable material, and may be of any shade, the said cover having a central opening to receive the ferrule or tip 11 so as to bear on the notch 10. 13 indicates a washer adapted to be secured onto a tubular extension 14 of the notch coöperating with the latter to clamp the cover. 15, 15 indicate one ele-

ment of a glove fastener secured in any preferred manner to the middle portion and adjacent to the free end of each rib 9. 16, 16 indicate the coöperating elements of the glove fastener secured at suitable points on the cover 12 so as to engage with the elements 15, 15. With this construction, it will be manifest that the cover may be readily detached or attached to the frame. The element 16 of the glove fastener located at the edge of the cover is elongated as shown. The inner end portion of this element is enlarged and adapted to interlock with the element 15 adjacent to the outer end of the rib. The reduced and elongated portion 18 extends to the top of the rib and presses the edge portion of the cover thereonto so as to prevent the edge from curling upwardly and exposing the tip of the rib when the device is in use.

19 indicates a chamber formed in the handle section 20 of the stick, said chamber being interiorly divided into compartments 21 adapted for the reception of coins of different denominations or sizes, and further subdivided into covered compartments 22 adapted to contain face powder, and the like. 24 indicates a hinged cover for the chamber, and 25 a spring catch adapted to lock the cover against accidental outward movement. 26 indicates a mirror on the inner surface of the cover, and the latter when closed forms part of the surface of the handle 20. With this construction, it will be seen that the components of an ordinary vanity case are associated with the handle and so located as to permit of ready access to the same when desired.

The handle section 20 is by preference secured onto the adjacent section of the stick a, so that it may be detached in the event of its being desired to apply the handle to another parasol, this construction also permitting of the handle to be sold as an article of manufacture independently of the para- sol.

27 indicates the runner which is herein shown as having a peripheral circular flange 28 adapted for connection to the inner ends of the stretchers 29. The runner has a hole 30 adapted to receive the sections 5. This contour of stick sections is invariably employed in the construction of sun shades and parasols, but it must be understood that I do not intend to limit my
